UNITED STATES PATENT OFFICE.

RICHARD H. SHADRICK, OF MINNEAPOLIS, MINNESOTA.

HYDROSTATIC GAS-HEATER CONTROL.

Application filed August 5, 1922. Serial No. 579,967.

To all whom it may concern:

Be it known that I, RICHARD H. SHADRICK, a citizen of the United States, residing at Minneapolis, in the county of Hennepin 5 and State of Minnesota, have invented certain new and useful Improvements in Hydrostatic Gas-Heater Controls, of which the following is a specification.

This invention relates to controls for 10 water heating systems and the main object is to provide a simple, practical and easily operated hydrostatically controlled means for lighting and extinguishing a gas burner used for heating water in private dwellings or 15 other places where comparatively small systems are installed. Further objects will be disclosed in the course of the following specification, and the device is clearly illustrated in the structure shown in the accompanying 20 drawings, wherein:

Fig. 1 is a diagrammatic view of a water system equipped with my improved hydrostatic control.

Fig. 2 is an enlarged detail section on 25 the line 2—2 in Fig. 3.

Fig. 3 is an enlarged vertical section on the line 3—3 in Fig. 1, and

Fig. 4 is an enlarged detail sectional view 30 of the plunger as shown on line 4—4 in Fig. 3.

Referring to the drawings more particularly and by reference characters, 5 designates a hot water tank which is fed with cold water through a pipe 6 and delivers the 35 heated water through a pipe 7 to the faucet or water valve 8. A gas heater 9, of common construction, is piped, by pipes 10 and 11, in circuit with the tank 5, the pipe 11 being connected with the pipe 7 so that the 40 hot water can be drawn off directly from the heater 9, or from the tank 5 when sufficient water therein has been heated. The heater 9 has a gas burner 12 at the end of a gas pipe 13. A pilot light 14 is provided which 45 burns at all times so that when a gas valve 15, soon to be described, is opened the burner will light, and when the valve is closed the burner will go out, leaving the pilot light burning.

50 The water inlet pipe 6 is normally a direct continuation of a pipe 6^a, but, when installing this device these pipes are separated (as shown) and pipes 16 and 17 are respectively connected to pipes 6 and 6^a. The

other ends of the pipes 16 and 17 are connected with the gas valve operating and controlling device, which is constructed and operated as follows:

The upper end of the device consists of a cylinder 18 which is tightly secured, by bolts 19, between a cap 20 and a casting 21, which close its ends. The pipe 16 screws into the cap 20, as at 16^a, and communicates with one end of the cylinder, while the pipe 17 connects as at 17^a, with a passage 22 in the casting 21, and thus communicates with the other end of the cylinder 18. A piston 23 is slideable in the cylinder 18, and is secured to one end of a plunger rod 24 which reciprocates in a packing nipple 25, and has a weight 26 at its lower end.

The piston 23 is provided with perforations 27 so that water can at certain times flow from the pipe 17 to the pipe 16, through the cylinder 18. But this flow is checked, at other times, by a valve 28, which is yieldingly separated from the piston by a coil spring 29.

When the plunger rod 24 is down, the valve 28 abuts against a sealing washer 30, 80 in the casting 21, and the weight of the member 26 causes the piston 23 to be pulled down against the valve, as in Figs. 1, 3 and 4, thus stopping passage of water through the piston; while if the piston is in its upper 85 position (see Fig. 2) the valve 28 is opened by a pin 31, which slides in the piston 23 and engages the cap 20.

The gas valve 15 is preferably a stock 90 valve of standard construction and design, in which a core 32, having a transverse passage 33 (Fig. 3), has a square turning shank 34. A square holedratchet member 35 is placed on the shank 34, and adjacent to it is rotatably secured, by a bolt 36, a lever member 95 37, which is provided with a pair of spring held pins 38^a adapted to engage against the ratchet 35 and thus actuate the valve. The outer end of the lever 37 is provided with a longitudinal slot 38 in which slidably 100 engages a pin 39 fixed on the rod 24.

The member 35 is further provided with a pair of radial pins 40, either of which, when in a vertical position, will form an electric contact with a brush member 41, which is secured to but insulated from the valve body as at 42. From the brush member 41 a wire 43 is run to a battery 44. A

wire 45, from the other pole of the battery, is connected with a bullseye light 46 (secured near the faucet or water valve 8) and from there is grounded as at 47, to complete the circuit.

When the device is completely installed as above described, and the pipe 6^a is connected with a city water supply main, the operation may be briefly described as follows:

When no water is being drawn the parts are in the position indicated in Figs. 1, 3 and 4; the faucet or water valve 8 is closed, the plunger rod 24 is down, the valves 15 and 28 are closed, the pilot light 14 is burning, and the light 46 is out. Now, when a person in the kitchen or bathroom of the house desires to heat water, he only has to open the faucet 8 for a moment and then shut it, with the result that the burner 12 and the light 46 will both light. By opening the faucet 8 and relieving the pressure in the pipe 6^a, a current will be caused to flow through the pipe 17, passage 22, cylinder 18, pipes 16 and 6, through the heater 9 and tank 5, and pipe 7 to the faucet 8. As the pressure in the pipe 16 is relieved the pressure from the pipe 17 will cause the piston 23 to rise until the pin 31 strikes the cap 20 and opens the valve, thus allowing free passage of the water through the system. This movement also causes the lever 37 to give a quarter turn to the valve plug 32, thus opening it, and causing the burner to light. One of the pins 40 will at this time contact with the brush 41, thus lighting the light 46, so that the operator will be notified that the gas is burning. When he has shut the faucet after first lighting the burner the parts will drop back to their normal position leaving the valve 15 open, as the pressure on each side of the piston will then be neutralized and the weight 26 will be sufficient to return the plunger. When sufficient water has been heated the gas can be turned off by again opening the faucet or water valve, which will of course be done anyway when the hot water is drawn. This, it is obvious, will also extinguish the light 46.

It will be noted that the device is connected with the cold water intake pipes 6, 6^a. It would of course be equally operative if it were cut in between the heater and the faucet, but in this event both hot and cold water would flow through the cylinder and would be more apt to injure the valves and piston because of the differences in temperature to which they would be subjected.

It is understood that suitable modifications may be made in the design and structural details of this invention, provided, however, that such modifications come within the spirit and scope of the appended claims. Having now therefore fully shown and described my invention, what I claim is:

1. The combination of a heater controlling valve, a second valve, and means controlled by the opening and closing of the second valve to open the first valve upon initial opening and closing of said second mentioned valve and to close the first valve upon a second operation of the second valve. 70

2. The combination of a water heater, a faucet for drawing water therefrom, a gas valve for controlling the flow of gas to the heater, a mechanism, controlled by operating said faucet, to open the gas valve upon initial opening and closing of the faucet and to close the gas valve upon a second operation of the faucet. 75

3. In combination in a water heating system, a water heater, a faucet communicating with the heater, a burner in the heater, and a hydrostatically operated means connected in circuit with the system for alternately lighting and extinguishing the burner by successive operations of the faucet. 85

4. In combination in a water heating system, a water heater, a faucet communicating with the heater, a burner in the heater, means, operatively controlled by the faucet whereby every other complete operation of the faucet will light the burner and each intervening operation of the faucet will extinguish the burner. 90

5. The combination with a water heating system, of a heater controlling valve having a plug, with a transverse passage, to be rotated in one direction, a faucet for drawing water from the system under pressure, and means operative by releasing the pressure in the system to rotate said valve plug a quarter revolution, whereby the valve is opened and closed alternately by successive releases of pressure. 100

6. The combination of a heater controlling valve having a rotating core, a cylinder connected in circuit with a water system, a piston slideable in the cylinder and actuatable upward by a flow of water in the system, and a clutch mechanism operated by said piston to turn said valve core, in quarter revolutions in the same direction, one quarter revolution for each upward movement of the piston. 110

7. In a water heating system, a hydrostatic valve actuating device, consisting of a cylinder connected in circuit with the water system, a piston slideable in the cylinder, a plunger rod secured at one end to the piston and having a weight at its other end, a pawl and ratchet mechanism for actuating said valve, and operative connection between the plunger rod and said mechanism. 120

8. In a water heating system, a heater for heating water, a faucet communicating with the heater for drawing water therefrom under pressure, a valve controlled gas burner under the heater, and an actuating member, actuatable by a movement of water 125

through the system, for alternately opening and closing the gas valve, respectively, upon successive complete operations of the faucet.

9. In combination with a hot water heating system having a heater, a hot water tank communicating therewith and a faucet communicating with the tank and heater for drawing water therefrom under pressure, of a burner in said heater and hydrostatically controlled means operative by each successive opening of the faucet for alternately lighting and extinguishing said burner.

10. In a water heating system, a hydrostatically operated valve actuating mechanism, consisting of a cylinder connected in circuit with the water system, a piston slideable in the cylinder, and operative connection between the piston and the valve to effect opening the latter with each alternate upward movement of the piston and to effect closing said valve upon each intermediate upward movement of the piston.

11. The combination in a water heating system, of a heater, a gas burner for heating the same, a valve regulating the flow of gas to the burner, a pilot light to light the burn-

er, a valve adapted to draw water under pressure from the system, a hydrostatically operated mechanism, controlled by said water valve, to open said gas valve upon initial 30 opening and closing of the water valve and to close the gas valve upon a second opening and closing of the water valve.

12. The combination in a water heating system, of a gas valve, a cylinder connected 35 in circuit with the water system, a piston slideable in said cylinder and actuatable upward by a movement of water through the system, means for normally retaining said piston in a downward position, said piston 40 having perforations for a flow of water therethrough, a valve normally closing said perforations, means for opening said valve when the piston is raised, and operative connection between the piston and said gas 45 valve, to open the latter by each alternate upward movement of the piston and to close the gas valve by each intervening upward movement of the piston.

In testimony whereof I affix my signature.

RICHARD H. SHADRICK.
